UNITED STATES PATENT OFFICE.

FRANCIS S. JOBSON, OF MENTONE, ALABAMA.

BURGLAR GUN.

1,422,865.

Specification of Letters Patent. Patented July 18, 1922.

Application filed February 18, 1922. Serial No. 537,572.

To all whom it may concern:

Be it known that I, FRANCIS S. JOBSON, a citizen of the United States, residing at Mentone, in the county of Dekalb and State of Alabama, have invented certain new and useful Improvements in Burglar Guns, of which the following is a full, clear, and exact description.

My invention relates to a burglar gun and has for its object to provide such a device which is simple in construction and operation and therefore of low cost in manufacture.

Another object of the invention is to provide a burglar gun or alarm which may be set in such manner as to merely give an alarm or to wound or kill an intruder.

A further object of the invention is to provide such a device with a safety latch whereby the same may be locked so as to avoid a premature explosion while handling, etc.

Other objects and advantages of the invention will be apparent from the following description when taken in connection with the accompanying drawing in which,

Figure 1 is a side elevation of the device.

Figure 2 is a plan view thereof.

Figure 3 is a fragmentary vertical section 30 through the gun showing the operation of the firing pin.

Figure 4 is a rear view partly in section, clearly showing the safety catch, and,

Figure 5 is a fragmentary section through 35 a modified form of the device.

Referring to the drawing more in detail, the numeral 1 designates a base member provided with screw holes 2, whereby the apparatus may be securely bolted to a counter, desk, or the like. Extending vertically from the base 1 are a plurality of standards or frame members 3, 4 and 5. The member 3 is bored horizontally to provide a socket 6 for the reception of a gun barrel 7, which latter is firmly held in place by a set-screw 8.

Formed in the opposite end of the standard 3 is a cylindrical passage 9 in which is mounted the firing pin 10 normally held in retracted position by the spring 11. A screw cap 12 is provided for locking the pin 10 and spring 11 in the cylindrical passage.

Mounted for longitudinal movement in the standards 4 and 5 is a plunger or rod 13 normally pressed toward the firing pin by means of the coil spring 14, which abuts the

standard 5 at one end and the pin 15 at the opposite end. The rod 13 is provided with a finger grip 16 for withdrawing the same against the pressure of the spring 14. 60

In order to hold the plunger in retracted position the same is provided with an annular groove 17 which receives an edge of the lever 18, the latter being pivoted at 19 to the rear of the standard 5. A bell-crank 65 lever 20 is pivoted to the side of the standard 5 and has its shorter arm 21 in engagement with the free end of the lever 18. It will thus be seen that when the bell-crank lever 21 is rocked on its pivot in the proper direction the lever 18 will be released from the groove 17 and permit the plunger 13 to move to the right (Fig. 1). For the purpose of moving the bell-crank 20 on its pivot 70 I provide an arm 22 pivoted to the top of the standard 5 at 23. This arm 22 engages the longer arm of the bell-crank 20 and has a cord or lanyard 24 secured to its free end. The opposite end of the lanyard is free to be secured to any part of the room, office, 80 or the like best suited for the purpose. The bell-crank 20 is also provided with an aperture 25 at its upper end for the direct connection of the lanyard 24 thereto when found desirable. A latch 26 is pivoted to 75 the rear of the standard and is adapted to engage the lever 18 and hold the same in the groove 17 to prevent accidental firing of the gun during handling.

In Figure 5 I have shown a slightly modified form of the invention wherein the firing pin 10' and plunger 13' are formed integrally. In other respects this form of the invention is identical with that previously described. 90

In operation, the base 1 is secured in the most advantageous position in a bank or the like. The barrel 7 is removed from the standard 3, loaded and replaced. The plunger 13 or 13', as the case may be, is drawn 100 against the pressure of the spring 14 until the groove 17 is under the lever 18; the latter then drops by gravity into the groove and thereby locks the plunger in retracted position. The free end of the lanyard 24 is 105 then taken to a suitable place in the room and secured with the lanyard reasonably taut. If it is intended to kill or seriously wound the trespasser the lanyard is placed in line with the barrel of the gun, while if it is intended to slightly wound or merely 110 frighten off the intruder the lanyard may

be placed at an angle to the barrel of the gun. In moving or otherwise working with the gun in loaded condition the latch 26 is swung into the position shown in Figure 4.

5 It will be seen from the foregoing that I have provided a simplified form of burglar gun which may be easily and quickly put in place, and furthermore one which is adjustable to either frighten, wound or kill an in-
10 truder.

In accordance with the patent statutes I have described what I now believe to be the best embodiment of the invention, but I do not wish to be understood thereby as limit-
15 ing myself or the scope of the invention, as many changes and modifications may be made without departing from the spirit of the invention, all such I aim to include in the scope of the appended claims.

20 What I claim as new and desire to secure by Letters Patent is:

1. A burglar gun including a base, a plu-
25 rality of standards extending upwardly therefrom, a barrel and a firing pin mounted in one of said standards, a spring-pressed plunger mounted on another of said standards and operatively connected with the fir-
ing pin, said plunger having a notch formed

therein, a lever normally engaging said notch, and a bell crank lever normally in contact with said first-mentioned lever and adapted to lift the same from the notch in said plunger.

2. A burglar gun including a base, a barrel and a firing pin mounted on said base, a standard, a spring-pressed plunger mounted thereon and operatively connected with the firing pin, said plunger having a notch formed therein, a lever pivoted to the rear of said standard and normally engag-
30 ing said notch, and a bell-crank lever piv-
35 oted at one side of the standard and nor-
mally engaging the first-mentioned lever.

3. A burglar gun including a base, a barrel and a firing pin mounted on said base, a standard, a spring-presser plunger mounted thereon and operatively connected with the firing pin, said plunger having a notch formed therein, a lever pivoted to the rear of said standard and normally engag-
40 ing said notch, a bell-crank lever pivoted at
45 one side of the standard and normally en-
gaging the first-named lever, and a latch
50 for locking said first-named lever in its
plunger engaging position.

FRANCIS S. JOBSON.
